UNITED STATES PATENT OFFICE.

GEORGE D. GALLAGHER, OF WASHINGTON, DISTRICT OF COLUMBIA, ASSIGNOR TO
WINCHESTER REPEATING ARMS COMPANY, OF NEW HAVEN, CONNECTICUT, A
CORPORATION OF CONNECTICUT.

BATTERY HAND-LAMP.

1,358,839.

Specification of Letters Patent. Patented Nov. 16, 1920.

Application filed June 8, 1920. Serial No. 387,278.

To all whom it may concern:

Be it known that I, GEORGE D. GALLAGHER, a citizen of the United States, residing at Washington, District of Columbia, have invented certain new and useful Improvements in Battery Hand-Lamps; and I do hereby declare the following to be a full, clear, and exact description of the invention, such as will enable others skilled in the art to which it appertains to make and use the same.

This invention in battery hand lamps relates particularly to arrangements for supporting within the metallic case of a lamp a conducting strip which completes the circuit between the switch mechanism mounted on the side of the case and the reflector at the front end of the case.

The usual arrangement for completing the circuit of a hand lamp having a metal case consists of a metal strip slidably mounted on the inner face of the case and adapted to be moved into or out of engagement with the reflector which is suitably insulated from the case upon the end of which it is supported, so that the circuit will be completed through the reflector only when the conducting strip is advanced into engagement with the reflector. In a hand lamp having a fiber case it is customary at the present time to provide a switch of the so called "dual" type, that is a switch comprising a part which automatically returns to open circuit position immediately upon being released after having been actuated to close the circuit of the lamp, and a part which upon actuation keeps the circuit closed indefinitely, thereby avoiding the necessity of holding the switch in circuit closing position when it is desired to produce a prolonged lighting of the lamp.

Since the case of such a lamp is formed of insulating material, the conductor which completes the circuit between the switch and one terminal of the lamp may be attached directly to the interior of the case, and no other insulation for the conductor need be provided.

When a switch of the "dual" type is applied to a metal case lamp it is necessary to insulate from the case the fixed conducting strip which is required for completing the circuit between the switch and the reflector.

It is an object of this invention to provide an arrangement for this purpose which shall consist of a comparatively small number of

parts, all of which may be quickly assembled within the case which need only be modified in a few particulars to adapt it to receive the strip and its associated insulation.

In accordance with the invention a number of pairs of parallel cuts are made in the case transverse to its axis, and the metal between the cuts is indented to form depressed straps, which, in conjunction with the portions of the case adjacent to the straps, form a channel extending longitudinally of the case and adapted to receive the conducting strip which is wrapped with non-conducting material, such as paper or the like, to insulate it from the adjacent portions of the case. The strip is thus held in place by the frictional engagement between it and the insulating wrapper, and between the latter and the case. The front end of the strip is preferably bent inwardly and held by its resiliency in engagement with the reflector, or other part of the lamp, which is in circuit with one terminal of the incandescent bulb. Any desired form of "dual" switch mechanism may be used in connection with the conducting strip, and the latter may be suitably constructed to coöperate with the movable element of the switch when it is depressed into circuit closing position, as by being formed with an offset portion projecting into the switch housing, or by being provided with a stud or rivet which extends into the housing, the case being cut away to allow for the passage of such offset portion or stud.

The particular nature of the invention, as well as other objects and advantages thereof, will appear more clearly from a description of certain preferred embodiments as shown in the accompanying drawings, in which;

Fig. 1 shows a hand lamp with one form of conducting strip applied thereto;

Fig. 2 is an enlarged view in longitudinal section of the strip and the switch associated therewith;

Fig. 3 is a view of the interior of the hand lamp;

Fig. 4 is an enlarged sectional view along the line 4—4 of Fig. 3; and

Fig. 5 is a detail view showing a modified form of strip.

The metal case hand lamps to which the invention may be applied may be of any construction. For the purpose of illustration

there is shown in Fig. 1 a hand lamp consisting of a metal case 10 adapted to contain a battery 11 composed of a number of dry cells placed end to end within a carton, in accordance with the usual construction of batteries of this character. One end of the case carries a cap 12 within which is a spring (not shown) for pressing the carbon terminal 13 at the other end of the battery against the inner terminal of an incandescent bulb 14 having its base screwed into a threaded socket at the inner end of a reflector 15. The reflector is provided with a flange adapted to rest upon the end of the case 10, and surrounding the reflector is a lens 16 which, together with the reflector, is held in place by a ring 17 screwed upon the end of the case.

The parts described above are of well known construction and may be varied at will without affecting the application of the present invention to the lamp. For the purpose of completing the circuit from the switch mechanism (to be hereinafter described) to the reflector 15 there is provided a metallic strip 18 surrounded by a wrapper 19 of suitable insulating material, such as paper or the like, and having its forward end bent inwardly as at 20 to engage the reflector. For the purpose of holding the strip and its wrapper in place there is provided a pair of straps 21 formed integrally with the casing by cutting the latter transversely along pairs of parallel lines and indenting the metal lying between the cuts of each pair. These depressed straps, in conjunction with the adjacent portions of the case, form in effect a longitudinal channel within which the conducting strip 18 and its insulating wrapper 19 may be inserted and held in place by frictional engagement between the strip and the wrapper and between the latter and the outer faces of the straps and the inner surface of the casing, the parts being so proportioned that the strip and its wrapper are thus firmly held in place without the necessity of providing other holding means, such as rivets or the like.

The casing 10 is provided with an aperture as at 22 adjacent to one of the straps, and the strip 18 is formed with a bend as at 23 extending through the aperture and adapted to be engaged by the movable member of a "dual" switch, which may be of any preferred construction. As here shown this switch consists of a housing 24 having attached thereto, as by means of a rivet 25, a spring finger 26, the free end of which is enlarged as at 27 and enters a correspondingly shaped opening 28 in the housing. Beneath the flat face 27 is an extension 29 adapted to be brought into engagement with the bent portion 23 of the conducting strip 18 when the spring finger is actuated by pres-

sure upon the flat face. Thus by depressing the spring finger, circuit may be established between the strip 18 and the casing 10 which is in electrical connection with one terminal of the battery through the cap 12 and the spring within the cap. Since the strip 18 is in engagement with the reflector 15 and the latter is in electrical connection with one terminal of the lamp, the circuit of the latter will be completed as long as the spring finger 26 is held in depressed position, but as soon as it is released the circuit will be broken and the lamp extinguished.

To provide for maintaining the circuit in closed condition independently of manual pressure upon the spring finger 26 there is slidably mounted upon the top of the housing a corrugated thumb piece 30 provided with tangs 31 which pass through slots in the housing and are bent together at their inner ends to form a lug 32 which normally lies within a slot 33 in the spring finger 26. When the latter is depressed the thumb piece 30 may be moved away from the flat portion 27 of the spring finger to cause the lug to engage the outer face of the spring finger to hold the latter permanently in contact with the bent portion 23 of the conducting strip 18, thus maintaining the circuit of the lamp in closed condition until the thumb piece 30 is restored to normal position.

In the modification shown in Fig. 5 the conducting strip 18 is provided with a rivet 34 which takes the place of the bent portion 23 shown in Fig. 2. The rivet is arranged to extend through the casing 10 and into the switch housing in order that it may be engaged by the end 29 of the spring finger 26 when the latter is depressed. In other respects the strip 18 and its wrapper 19 are constructed as described above and held in place within the casing by straps formed out of the metal of the latter, but in some cases it may be more convenient to use a rivet instead of producing a bond in the conducting strip as described in connection with Fig. 2.

While the invention has been shown in connection with a metal case lamp in which the circuit of the bulb is completed through the reflector, it will be understood that it is equally applicable to a lamp in which the bulb is insulated from the reflector and its circuit is completed through other metallic parts. It will also be understood that various changes may be made in the details of construction without departing from the principle of the invention as shown in the appended claims.

I claim:

1. In a battery hand lamp comprising a case having a battery therein, a reflector mounted upon one end of the case and

- switch mechanism mounted on the exterior of the case, a conducting member extending between the switch mechanism and the reflector, said member being surrounded by insulating material and held in fixed position within the case by members formed out of the material thereof.
2. In a battery hand lamp comprising a case having a battery therein, a reflector mounted upon one end of the case and switch mechanism mounted on the exterior of the case, a conducting member surrounded by insulating material extending between the switch mechanism and the reflector, and held in fixed position within the case by members formed out of the material thereof, said member being provided with an offset portion extending through an aperture in the case, and adapted to be engaged by a movable part of the switch mechanism.
3. In a battery hand lamp comprising a case having a battery therein, a reflector mounted upon one end of the case and switch mechanism mounted on the exterior of the case, a conducting member extending between the switch mechanism and the reflector, said member being surrounded by insulating material and held in fixed position within the case by indented transverse strap like portions of the material of the case.
4. In a battery hand lamp the combination of a case provided with indented portions extending transversely thereof, a conducting member held in place between the indented portions and the inner surface of the case, insulating material between the conducting member and the adjacent surfaces of the case and the indented portions, a reflector mounted at one end of the case and engaged by one end of the conducting member, and switch mechanism mounted on the case and provided with a part adapted to be brought into engagement with the conducting member.
5. In a battery hand lamp the combination of a case provided with indented portions extending transversely thereof, a conducting member held in place between the indented portions and the inner surface of the case, and provided with an offset portion projecting through an aperture in the case, insulating material between the conducting member and the adjacent surfaces of the case and the indented portions, a reflector mounted at one end of the case and engaged by one end of the conducting member, and switch mechanism mounted on the case and provided with a part adapted to be brought into engagement with the offset portion of the conducting member.
6. In a battery hand lamp the combination of a case provided with indented portions extending transversely thereof, a conducting member held in place between the indented portions and the inner surface of
- the case, insulating material surrounding the conducting member to keep it out of electrical contact with the adjacent surfaces of the case and the indented portions, a reflector mounted at one end of the case and engaged by one end of the conducting member, and switch mechanism mounted on the case and provided with a part adapted to be brought into engagement with the conducting member.
7. In a battery hand lamp the combination of a conducting member surrounded by a wrapper of insulating material, a case provided with depressed portions constituting in connection with the adjacent portions of the case a channel within which the conducting member and its wrapper are held by frictional engagement, a reflector mounted at one end of the case and engaged by one end of the conducting member, and switch mechanism mounted on the case and provided with a part adapted to be brought into engagement with the conducting member.
8. In a battery hand lamp comprising a case having a battery therein, an incandescent bulb at one end of the case and switch mechanism mounted on the exterior of the case, a conducting member for completing circuit between the bulb and the switch mechanism, said member being surrounded by insulating material and held in fixed position within the case by members formed out of the material thereof.
9. In a battery hand lamp comprising a case having a battery therein, an incandescent bulb at one end of the case and switch mechanism mounted on the exterior of the case, a conducting member, surrounded by insulating material, for completing circuit between the bulb and the switch mechanism, and held in fixed position within the case by members formed out of the material thereof, said member being provided with an offset portion extending through an aperture in the case, and adapted to be engaged by a movable part of the switch mechanism.
10. In a battery hand lamp the combination of a case provided with indented portions extending transversely thereof, a conducting member held in place between the indented portions and the inner surface of the case, and provided with an offset portion projecting through an aperture in the case, insulating material between the conducting member and the adjacent surfaces of the case and the indented portions, an incandescent bulb at one end of the case in circuit with the conducting member, and switch mechanism mounted on the case and provided with a part adapted to be brought into engagement with the offset portion of the conducting member.

In testimony whereof I affix my signature.
GEORGE D. GALLAGHER.
